Fig. 10

Fig. 12

Fig. 11

FIG. 1 is a top plan view of a sectional panel element of a fiberglass reinforced polyester housing structure showing my new design;

FIG. 2 is a right side elevation thereof;

FIG. 3 is a front elevation thereof;

FIG. 4 is a bottom plan view thereof;

FIG. 5 is a left side elevation thereof;

FIG. 6 is a rear elevation thereof;

FIG. 7 is a top plan view of a modified form of the design shown in FIG. 1;

FIG. 8 is a left side elevation thereof;

FIG. 9 is a rear elevation thereof;

FIG. 10 is a bottom plan view thereof;

FIG. 11 is a right side elevation thereof;

FIG. 12 is a front elevation thereof;

FIG. 13 is a cross-section view thereof taken along line 13-13 of FIG. 2; and

FIG. 14 is a cross-section view thereof taken along line 14-14 of FIG. 8.

I claim:

The ornamental design for a sectional panel element of a fiberglass reinforced polyester housing structure, as shown and described.
